COOKING UTENSIL HANDLE OR THE LIKE

James C. Baker, South Gate, Calif., assignor to
Norris Stamping & Manufacturing Company,
Los Angeles, Calif., a corporation of California

Application May 5, 1950, Serial No. 9,724

Term of patent 14 years

(Cl. D44—29)

To all whom it may concern:

Be it known that I, James C. Baker, a citizen of the United States, residing in South Gate, county of Los Angeles, State of California, have invented a new, original, and ornamental Design for a Cooking Utensil Handle or the like, of which the following is a specification, reference being had to the accompanying drawing, forming part thereof.

Figure 1 is a perspective view of a cooking utensil handle embodying my new design;

Figure 2 is a side elevational view;

Figures 3 and 4 are, respectively, top and bottom plan views; and

Figures 5 and 6 are end elevational views thereof taken, respectively, from the left and right-hand ends of Figure 2.

The broken line showing is for illustrative purposes only.

I claim:

The ornamental design for a cooking utensil handle or the like, substantially as shown and described.

JAMES C. BAKER.
